T. LUND

HEEL BREASTING MACHINE

Filed Nov. 15, 1919

Fig. 1.

UNITED STATES PATENT OFFICE.

THOMAS LUND, OF BEVERLY, MASSACHUSETTS, ASSIGNOR TO UNITED SHOE MANUFACTURING CORPORATION, OF PATERSON, NEW JERSEY, A CORPORATION OF NEW JERSEY.

HEEL-BREASTING MACHINE.

Application filed November 15, 1919. Serial No. 338,291.

To all whom it may concern:

Be it known that I, THOMAS LUND, a citizen of the United States, residing at Beverly, in the county of Essex and State of Massachusetts, have invented certain Improvements in Heel-Breasting Machines, of which the following description, in connection with the accompanying drawings, is a specification, like reference characters on 10 the drawings indicating like parts in the several figures.

This invention relates to machines for making spring heel lifts and more particularly for beveling or "wedge shaping" the 15 breast or straight edge portions of such lifts.

In spring heel shoes, the break of the heel inclines gradually from the tread surface of the heel and merges into the surface of 20 the shank or bottom of the shoe in front of the heel. The spring heel lifts which are secured to the heel portion of the shoe and define the gradation or incline at the break of the heel, however, are died out of 25 the stock or sheet material by a cut extending directly from one surface to the other, and the lifts present substantially uniform thickness about the contour and breast or straight edge portions thereof. To secure 30 the gradual incline along the break of the heel, the breast or straight edge portion of the spring heel lifts is trimmed or given a bevel more or less emphasized in accordance with the degree of inclination desired, 35 and since such spring heel lifts are usually secured between the heel seat of the shoe and heel portion of the outersole, the bevel or wedge shape extends from a line well back of the breast edge at one surface to a 40 line at or close to the edge of the breast at the opposite surface, to avoid the existence of any opening or recess at the beveled edge of the lift due to the configuration of the outersole at the break of the heel. In some 45 cases one or more spring lifts may be employed and in other instances one or more of such lifts may be secured to the heel portion outside the outersole, but in any event the bevel or wedge incline should be in conformity with the spring character desired 50 for the heel. The degree of bevel or incline to be given the breast edge of the spring heel lift will depend upon several

factors, amongst which may be instanced the height or thickness of the lift, the particular spring or incline at the break of the heel, size and style of shoe; and one object of the present invention is to provide a simple and efficient machine whereby any desired bevel or incline may be given the 60 breast or straight edge portion of spring heel lifts.

An important feature of the invention, therefore, consists in a novel construction of rest on which a spring heel lift may be 65 clamped and that is adjustable to different inclinations relative to the path of a beveling knife.

This feature of the invention may be 70 variously contrived, but in the present instance is carried into effect by a plate which is adjustably secured to the machine frame and has projecting therefrom the spring heel rest, the adjustment of the plate and, 75 perforce, the spring heel rest, being about an axis passing transversely of the spring heel rest approximately at the line of contact between a spring lift and the surface of the rest.

Another important feature of the invention 80 consists in a positioning lip on the rest against which the breast edge of the heel or heel lift abuts when in breasting position and a clamp constructed and arranged to apply pressure longitudinally to the heel 85 to hold it against the lip at the same time that it applies downward clamping pressure to the heel. Preferably the lip has a substantially sharp upper edge which extends slightly above the plane of the surface on 90 which the heel or lift rests, said edge being in axial alignment with the axis about which the plate is adjustable and concaved to conform to the knife face which is next to the heel or lift, so that the knife cooperates with the said edge in the various adjustments of the plate to effect a shearing 95 cut at the completion of its stroke. The rib or lip acts in addition to its cooperation with the knife to protect the lower edge of the 100 breast face of the heel by which it is positioned so that no material is removed therefrom. This results in a saving of stock since a heel of any size will have enough stock removed to form the desired bevel of 105 its breast face and no more.

Another important feature of the invention consists in a clamp which is adjustable towards and from the surface of the adjustable heel rest so that spring heel lifts of 5 different heights may be treated and which is adjustable with the plate to maintain the relation between the clamp and the plate relatively unchanged.

Other features and novel combinations of 10 parts will hereinafter be described in addition to the above, and then the novel characteristics of the invention will be definitely set forth in the claims.

In the drawings only sufficient parts of 15 a machine embodying the invention are illustrated to make clear the construction, mode of operation of the invention, and the association thereof with the co-acting parts. This machine may be either manually or 20 power operated.

In the drawings:

Fig. 1 is a perspective view of a machine embodying the present invention;

Fig. 2 is a side view in detail with parts 25 broken away showing more particularly the positioning lip and its relation to the other parts.

The machine frame 1 of suitable construction rises from a base or support, and is 30 provided with a guide-way 2, of which there may be two or more, for guiding the reciprocating movements of a knife carrying head 3. The head 3 may be reciprocated by any suitable means and to it is secured the knife 4. In the present instance of the invention 35 the head 3 has a bridge-piece 5, to which the knife 4 is secured by means of clamping bolts 6 which pass through the bridge 5 and clamp the knife 4 against a backing 7 carried by the head. Overhanging the upper 40 end of the knife 4 is an abutment 8 through which extend the stop screws 9 adapted to bear upon the upper edge of the knife, the construction being such that by proper 45 manipulation of the clamping screws 6 and adjusting screws 9, the knife 4 may be adjusted and secured in desired position relative to the reciprocating head 3.

Adjustably connected to the machine 50 frame is the carrier or plate for the spring lift rest, which is adjustably secured to the frame to provide for varying inclinations of spring heel lifts on the rest relative to the predetermined path of the knife. In 55 the present instance the carrier or plate 10 is of general disk form and is provided about its marginal portions with slots 11 formed in the arc of a circle, the centre of which is the axis about which the carrier or plate 10 is adjustable. Passing through the curved 60 slots 11 are the bolts 12 having suitable nuts and washers 13 for clamping the plate in position to which it has been adjusted.

Extending laterally from the face of the 65 plate 10 is the spring heel rest 14. The rest

14 may be connected to the plate in appropriate manner to withstand the cutting action of the knife, but in the present instance of the invention it is formed integral with the plate 10, thereby presenting a 70 simple, cheap, and effective construction. The supporting surface 15 of the rest 14 is preferably formed flat for properly supporting one surface of a heel lift mounted on the rest, and in order to position the heel 75 lift on the rest, suitable guides or gages may be employed. In the present instance, the spring heel lift 14 is shown as formed of four pieces and is positioned upon the rest 14 by means of side gages 17, a breast beveling lip 14' and an end gage 16. The gage 16 may be of the usual character employed in positioning lifts upon their supports and adapted to engage the rear contour portion 80 of the lifts, while the side gages 17 may be of appropriate character to locate the spring heel lifts laterally of the knife 4. The rear gage 16 may be of the usual construction 85 and yieldingly mounted to permit the lift to be placed upon the rest, while the side gages 17 are preferably formed or provided with adjusting wing nuts 19 for adjusting the gages laterally of the heel. The lip 14' extends slightly above the surface of the rest 90 14 and has a substantially sharp upper edge which lies in alinement with the axis about which the plate 10 is adjustable and also in the plane of the adjacent face of the knife and the knife edge so that the knife cooperates with the edge of the lip in effecting a 95 shearing cut upon the heel.

The carrier or plate 10 has mounted thereon a clamp for engaging the exposed surface of the spring heel lift and clamping it upon the rest. In the present instance of the invention the plate 10 has a portion 20 provided with a slot 21 through which passes the bolt 22 which constitutes the axis about which the clamp 23 may rock. The clamp 23 has a sleeve portion 24 and an eccentric or clamping section 25 which engages the exposed surface of the spring heel lift on the rest. The clamp is adjustable on the carrier or plate 10 to different positions 100 towards and from the surface of the rest, and in the present instance such adjustment is varied by the slot 21 through which the bolt 22 passes, the head of the bolt taking into the guides 26 at the back of the slot, the construction being such that by loosening 105 the nut 27 the clamp may be adjusted in the slot 21 and then secured in adjusted position.

Extending from the clamp is an operating arm 28 which is normally under the influence of a spring 29 tending to move the clamp into unclamping position. In the illustrated instance the spring 29 has one end 30 secured to the operating arm 28 and the other end 31 secured to a pin 32 mounted 110 115 120 125 130

on the machine frame, the construction being such that the impulse of the spring 29 tends normally to throw the clamp into unclamping position. Secured to the operating arm 5 28 is a rod 33 which may be actuated by any suitable means, one good form of which may be a treadle, not shown. When the clamp is operated to clamp the heel the frictional engagement of the portion 25 of 10 the clamp with the heel will force the heel towards the lip 14' and cause engagement of the lower edge of the heel breast with the lip throughout its extent before the said portion begins to slip upon the heel to apply 15 clamping pressure to the heel to hold it in position for the action of the knife.

The position of the rest 14 relative to the carrier or plate 10 is such that when a spring heel lift is mounted on the rest, its breast 20 will be in the axis of adjustment of the plate 10. This axis thus passes transversely of the rest 14 and substantially along the line of contact between the surface of the rest and the breast edge of the lift supported by the 25 rest, or more particularly along the upper edge of the lip 14', the effect being that when the plate and rest are adjusted to different positions of inclination about the axis, the cutting operation of the knife 4 will commence its beveling or wedge-shaping cut well 30 back of the exposed edge of the spring heel lift and terminate its cutting action adjacent the line of contact between the surface of the spring heel lift and rest, or more particularly along the edge of the lip 14'. Since the clamp for securing the lift upon 35 the rest is mounted on the carrier or plate 10, it maintains its position relative to the rest as the plate and rest are adjusted to 40 change the inclination or plane of cut, and the adjustable connection between the plate or carrier 10 and the clamp provides a ready means for accommodating the machine for the treatment of spring heel lifts of different height or thickness.

Having described my invention what I claim as new and desire to secure by Letters Patent of the United States is:

1. In a machine for making spring heel 50 wedges, the combination of a knife movable in a predetermined path, a rest for supporting spring heel lifts for the action of the knife and having a fixed lip to position the breast of the lift, the rest being adjustable about an axis passing transversely of the 55 rest along that edge of the lip which is more distant from the rest, and means for clamping the spring heel lift on the rest.

2. In a machine for beveling the breast 60 edge of a spring heel lift, the combination of a knife movable in a predetermined path, a rest for supporting a spring heel lift for the action of the knife, means for adjustably connecting the rest to the machine frame for 65 movement about an axis passing trans-

versely of the rest through the line of cut made by the knife, and a clamp carried by the rest for engaging the upper surface of the spring heel lift and clamping it upon the rest in any position of rest adjustment, 70 said clamp having a movement lengthwise of the heel while in engagement with the heel.

3. In a machine for making spring heel wedges, the combination of a knife movable 75 in a predetermined path, a rest for supporting spring heel lifts for the action of the knife, a fixed lip for positioning the spring heel lift on the rest, the rest being adjustable about an axis passing transversely of the rest along the free edge of the lip, and means for clamping the spring heel lift against the lip and on the rest.

4. In a machine for beveling the breast edge of a spring heel lift, the combination of 80 a knife movable in a predetermined path, a rest for supporting a spring heel lift for the action of the knife, means for adjustably connecting the rest to the machine frame for varying the inclination of the spring 85 heel lift relative to the path of the knife that the bevel given to the breast edge of the lift may be given a wedge form in substantial accordance with the inclination at the break 90 of the heel, and a clamp carried by said rest and constructed and arranged to be manually operated relatively thereto for engaging the top surface of the spring heel lift on the rest in any inclination of its adjustment and for clamping the heel on the rest, said 95 clamp being arranged to apply a component of clamping pressure lengthwise of the heel.

5. In a machine for beveling the breast edge of a spring heel lift, the combination of 100 a knife movable in a predetermined path, a plate carrying a rest for supporting one surface of a spring heel lift, means for connecting the plate to the machine frame for adjustment about an axis passing transversely of the rest along the breast line of a spring 105 heel lift on the rest, a cam-shaped clamp pivoted on and adjustable with the plate for engaging the opposite surface of the spring heel lift in any position of inclination of the rest, and means for operating the clamp 110 positively to clamp the heel on the rest.

6. In a machine for beveling the breast edge of a spring heel lift, the combination of 120 a knife movable in a predetermined path, a stationary rest for supporting a spring heel lift, for the action of the knife, means for adjustably connecting the rest to the machine frame for varying the inclination of the spring heel lift relative to the path of the knife that the bevel given to the breast edge of the lift may be given a wedge form in substantial accordance with the inclination at the break of the heel, and a swinging 125 clamp carried by said rest for engaging the exposed surface of spring heel lifts of a 130

given height on the rest in any inclination of adjustment, the clamp being bodily adjustable towards and from the surface of the rest to accommodate spring heel lifts of different heights.

7. In a machine for beveling the straight edge of a spring heel lift, the combination of a knife movable in a predetermined path, a plate carrying a rest for supporting a spring heel lift, the plate being adjustable about an axis passing transversely of the rest for presenting a spring heel lift in different inclinations to the path of the knife, and a rocking clamp carried by the plate for clamping the spring heel lift to the rest in any position of adjustment of the plate, the axis of the clamp being adjustable on the plate towards and from the surface of the rest to accommodate spring heel lifts of different heights.

8. In a machine for beveling the straight edge of a spring heel lift, the combination of a knife, a plate having a lift rest extending therefrom for supporting a spring heel lift, means for adjustably connecting the plate to the machine frame for changing the angular relation of the rest relative to the path of the knife about an axis extending transversely of the plate along the straight edge of the lift on the rest, and a rocking clamp, said plate having a slotted portion, and the axis of the clamp being adjustable along the slotted portion towards and from the rest.

9. In a machine for beveling the straight edge of a spring heel lift, the combination of a knife movable in a predetermined path, a disk-like plate carrying a rest for a spring heel lift, and provided with slots curved about a centre passing transversely of the rest, bolts passing through said slots for securing the plate in adjusted position, a rocking clamp carried by said disk-like plate above the rest, and means for operating the rocking clamp to secure a spring heel lift to the rest in any of its inclined positions of adjustment relative to the path of the knife.

10. In a machine for removing material from the breast end of a heel, the combination of a reciprocating knife, a heel rest for one surface of the heel, said rest having a fixed stop to limit endwise movement of the heel toward the knife, and a clamp constructed and arranged to engage the opposite surface of the heel and acting to move the heel first lengthwise into engagement with the stop and then to apply clamping pressure to hold the heel on the rest during the action of the knife.

11. In a machine for removing material from the breast end of a heel, the combination of a reciprocating knife, a heel rest for one surface of the heel, a member mounted on a single axis extending transversely of the heel and having a cam face for engagement with the opposite surface of the heel,

and manually operated means for turning the member to clamp the heel on the rest.

12. In a machine for removing material from the breast end of a heel, the combination of a reciprocating knife, a heel rest for the surface of the heel, said rest having a stop to limit endwise movement of the heel toward the knife, a cam member on an axis extending transversely of the heel and movable toward the knife to engage the heel, the cam member acting first to slide the heel toward the stop and then to apply positive clamping pressure to the heel to hold it on the rest, and means for operating the cam member to do its work.

13. In a machine for beveling spring heels, the combination of a knife movable in a fixed path, and a heel rest inclined to the path of the knife having a breast engaging lip the free edge of which is arranged to clear the edge of the knife and cooperate therewith to effect a shearing cut in removing the portion of the heel extending beyond said edge and into the path of the knife, the lip causing the portion of the breast engaging the lip to be unaffected by the knife.

14. In a machine for beveling spring heels, the combination of a flat knife movable in a fixed path, and a heel rest inclined to the path of the knife and having a rigid lip thereon of uniform height arranged on the side of the knife toward the heel, said lip serving to position the breast portion of the heel relatively to the knife while exposing substantially its entire breast portion to the action of the knife so that the portion not engaged by the lip will be removed by the action of the knife and the relatively small portion of the breast protected by the lip will be unaffected.

15. In a machine for removing material from the breast end of a heel, the combination of a reciprocating knife, a heel rest having a rigid lip to limit endwise movement of the heel toward the knife and adjustable about an axis coinciding with the free edge of the lip, a cam member on an axle on an extending transversely of the heel and carried by the rest, the cam member being movable toward the knife to engage the heel and acting first to slide the heel toward the lip and then applying positive clamping pressure to the heel to hold it on the rest, and means for operating the cam member to do its work.

16. In a machine for beveling spring heels, the combination of a knife movable in a fixed path, a heel rest inclined to the path of the knife having a breast engaging lip the free edge of which is arranged to clear the edge of the knife and cooperate therewith to effect a shearing cut in removing the portion of the heel extending beyond said edge and into the path of the knife, the lip causing the portion of the breast engaging

the lip to be unaffected by the knife, and a clamp acting to force the heel against the lip.

17. In a machine for beveling spring heels, the combination of a knife movable in a fixed path, a heel rest inclined to the path of the knife and having a rigid lip thereon arranged on the side of the knife toward the heel and serving to position the breast portion of the heel relatively to the knife so that the portion not engaged by the lip will be removed by the action of the knife and the relatively small portion of the breast protected by the lip will be unaffected, and a manually operated clamp acting to force the heel against the lip and hold it in position during the action of the knife. 15
- 10 In testimony whereof I have signed my name to this specification.

THOMAS LUND.

Certificate of Correction.

It is hereby certified that in Letters Patent No. 1,477,574, granted December 18, 1923, upon the application of Thomas Lund, of Beverly, Massachusetts, for an improvement in "Heel-Breasting Machines," an error appears in the printed specification requiring correction as follows: Page 4, line 112, claim 15, strike out the words "axle on an" and insert instead the word *axis*; and that the said Letters Patent should be read with this correction therein that the same may conform to the record of the case in the Patent Office.

Signed and sealed this 1st day of April, A. D. 1924.

[SEAL.]

KARL FENNING,
Acting Commissioner of Patents.
